FIG. 1 is a side elevational view of an internal combustion rotary engine rotor housing according to our new design the opposite side being a mirror image thereof;

FIG. 2 is an end elevational view thereof taken along the line 2—2 in FIG. 1;

FIG. 3 is a sectional view thereof taken along the line 3—3 in FIG. 1;

FIG. 4 is an end elevational view thereof taken along the line 4—4 in FIG. 1;

FIG. 5 is a perspective view thereof;

FIG. 6 is a top plan view thereof taken along the line 6—6 in FIG. 1; and

FIG. 7 is a bottom plan view thereof taken along the line 7—7 in FIG. 1.

This is a continuation-in-part of design application Ser. No. 478,956, filed June 13, 1974 and now abandoned.

We claim:

The ornamental design for an internal combustion rotary engine rotor housing, substantially as shown and described.
